Primary Examiner—Lucy Lieberman*Attorney, Agent, or Firm*—Pollock, Vande Sande & Priddy[57] **CLAIM**

The ornamental design for a bottle, as shown and described.

DESCRIPTION

FIG. 1 is a front elevational view of a bottle showing my new design, the rear, left and right sides are the same except for the conventional screw threading on the bottle neck;
FIG. 2 is an elevational view showing the bottle of FIG. 1 rotated 45 degrees to the left;
FIG. 3 is a bottom plan view thereof; and,
FIG. 4 is a top plan view thereof.
